UNITED STATES PATENT OFFICE

MAX KRISSIEP, OF WYOMISSING, PENNSYLVANIA, ASSIGNOR TO TEXTILE MACHINE WORKS, OF WYOMISSING, PENNSYLVANIA, A CORPORATION OF PENNSYLVANIA

TUBULAR-BRAIDING MACHINE

Application filed November 7, 1929. Serial No. 405,304.

The invention relates to braiding machines of the type used in manufacturing rubber tubing such as is used for garden hose, fire engine hose, air brake couplings and the like.

5 The invention has for a primary object to provide an improved machine of this character by means of which a more perfect and dependable product may be produced; and by means of which the manufacture thereof 10 may be facilitated and rendered more economical.

A further object is to provide a machine of this character with adjustable mechanism whereby its operation may be automatically discontinued upon the completion of any determined length of tubing up to the capacity 15 of the machine and whereby the machine may be readily adapted to the manufacture of tubing of various diameters, thicknesses 20 and bores.

These objects are accomplished by mechanism an embodiment of which is illustrated in the accompanying drawings and herein-after described in reference thereto; the novelty 25 of the invention herein illustrated being set forth in the appended claims. In the drawings:

Fig. 1 illustrates in side elevation, a braiding machine of a type to which the invention 30 is applicable, the take off mechanism being shown fragmentarily.

Fig. 2 is a section through the braiding mechanism of the machine on the line 2—2 of Fig. 1.

35 Fig. 3 is a broken side elevation of the take off mechanism per se.

Fig. 4 is a plan view, and Fig. 5 is an end elevation of the same.

Fig. 6 is a fragmentary section through the 40 take off mechanism on line 6—6 Fig. 4 showing on an enlarged scale the connection between the mandrel and draft means.

Fig. 7 is a section on line 7—7 of Fig. 3 on the same scale as Fig. 6, showing the relation 45 of the take off carriage to the automatic stop operating mechanism.

Fig. 8 is an enlarged plan section through the braiding mechanism of the machine on the line 8—8 Fig. 1.

50 Fig. 9 is a detail of a release for the auto-

matic stop mechanism on line 9—9 of Fig. 8.

The machine herein illustrated and described has in common with machines heretofore known, a braiding unit A, a mandrel B in the nature of a long rod, and take off mechanism C; the mandrel being adapted to be moved along a course and tubing formed thereon by first applying a layer of unvulcanized rubber thereto, after which a covering of several successive layers is braided thereon. Upon completion of the braiding a further coating of unvulcanized rubber is laid upon the braiding and the whole vulcanized before the removal of the mandrel.

In machines such as heretofore used, difficulty has been experienced in removing the finished product from the mandrel owing to distortions in the rubber and its adhesion to the mandrel caused by the pressure exerted thereon,—by the usual mandrel feeding mechanism.

In an attempt to overcome these difficulties, the mandrel has been drawn along its course by a cable attached to its forward end. This method has resulted in an uneven and 75 undependable braiding due to the stretching of the cable with a consequent uneven feed of the mandrel.

The present machine overcomes the difficulties of both of these previously used methods 80 by providing a draft means in the nature of a belt made up of inelastic rigid links to which the mandrel is connected and drawn along its course. In addition to this the invention provides in the take off mechanism a vertically adjustable supporting track along 85 which the mandrel is drawn, after it leaves the braiding unit with the tubing formed thereon, and by this arrangement the manufacture of tubing of various diameters is provided for. The provision of means adapting the machine to the facilitous manufacture of tubing varying in thickness and bore is provided for in a carriage attachable to the endless belt and having means adjustable vertically thereon for attaching mandrels of varying diameter thereto.

I will now proceed to describe the machine with the above and other inventive features applied thereto, beginning with the braiding unit 95 100

which consists of circular stationary supports 10 for the braiding mechanism arranged in spaced parallel vertical planes transversely of the unit and consisting themselves of spaced parallel walls 11 one of which is provided with the usual raceways 12 for the support and determinate guidance of yarn carriers 13 in their braiding movements. These supports also carry between their spaced walls 11 the usual horn gear mechanism 14 for actuating the carriers which in turn are driven by the power shaft 15 extending longitudinally of the braiding unit through gears 16 on the said shaft in mesh with gears 17 on shafts 18 journaled in the walls 11 of the supports, the shaft 18 carrying a gear 20 meshing with one of a train of gears 21, each gear of which is connected through a sleeve 22 with a horn gear 23. For stability, the supports 10 are interconnected at the top of the unit by rods 24 and at their bottoms are supported on the base 26 by pedestals 25.

The power shaft is itself driven from a suitable source of energy, not shown, through a belt 27, trained about a pulley 28 fast to the shaft 15. Adjacent this pulley on the said shaft is an idler pulley 29 on to which the belt may be shifted when the machine is to be automatically stopped; the shaft 15 may also be turned manually by hand wheels 30 secured thereto.

The usual automatic stop or cut out mechanism operable upon the breaking of a thread is provided and consists of the belt shifting arms 31 secured to a rod 32 movable lengthwise of the machine under influence of a spring 33. Shifting of this rod is normally prevented by an arm 34 secured to a shaft 35 journaled in bearings 36 extending lengthwise of the machine and resting in a notch 37 in rod 32 as shown in Fig. 9. The withdrawal of the arm from the notch is caused by the turning of members 38 on their pivots 39 upon the breaking of a thread in a well known manner; the movement being communicated to arm 34 by suitable means as links 40 connecting arm 34 with arms 41 movable with the members 38.

Resetting of the rod 32 after the mechanism has been stopped for any reason and consequent shifting of belt 27 back to pulley 28 is accomplished by manipulation of rock shaft 42 journaled to the base 26, said shaft having a hand lever 44 at one end and an arm 45 at the other end pivotally connected to the rod as at 46.

The supports 10 are centrally apertured as at 47 to accommodate passage of mandrel B axially therethrough; the mandrel being supported in passing by pulleys 48 rotatable on arms 49 secured to the supports.

The take off mechanism C associated with the braiding unit includes supporting structure standards 50 arranged in pairs spaced along the course of mandrel B, the standards

of each pair being in opposition on either side of the said course; said standards being secured together at their upper ends by rods 51 and their lower ends by the base member 52.

Supported by the standards is a track comprised of angle brackets 53 and channel beams 54 extending the length of the take off structure and connected together by bolts 55. Angle irons 54 have flanges on their upper edges affording a support or runway for the carriages 57 as they pass along their course carrying with them the braided mandrel. The carriages are connected to and drawn along by an endless chain 58 comprised of pivotally connected nonelastic links trained about sprockets 59 secured on shafts 60 which are journaled in the supporting structure. The non-elastic qualities of the links insure an unvarying pull upon the mandrel with a consequent uniformity of its movement along its course resulting in a uniformity of the braiding.

The chain is driven by a shaft 61 extending lengthwise of the machine, through a worm 62 on shaft 61 and a wormwheel 63 on one of the shafts 60. Shaft 61 in turn is driven from power shaft 15 through gear 64, on shaft 15, meshing with gear 65 and secured to shaft 66 journaled in a braiding unit support which latter shaft is in driving connection with shaft 61 through sprocket wheels 67 and 68 and sprocket chain 69.

The lower reach of the chain 58 is passed over sprockets 70 adjustably mounted by means of brackets 70^a on the angle irons 54 tensioning the said chain about the sprockets 59. Secured to rods 51 at the end of the take off mechanism adjacent the braiding unit is a former ring 71 of usual construction and purpose.

As heretofore set forth, it is important in the production of lengths of tubing such as herein suggested, that no adherence of the tube to the mandrel or other obstruction to the removal of the tube therefrom should be present when this stage of its production is reached.

In the present embodiment of the invention these objectionable features are avoided by threading the mandrel B at one end as shown at 72 in Fig. 6 of the drawings, and providing in connection therewith a connecting member 74 having a correspondingly threaded socket 73; the member 74 being rotatably mounted in a carriage 75 which comprises a flat portion 76 adapted to rest upon the endless chain 58 and a vertically extending portion 77 in a vertical slot 78 of which, the socketed connecting member 74 is rotatably and slidably mounted.

This slot is of sufficient extent and width to accommodate connecting members of varying diameter to be used with mandrels

of correspondingly varying diameter and to adapt the position of the said connecting member to the position of the mandrel for varying thicknesses of tubing being fabricated thereupon. The carriage is provided with a hook 79 on its under side by means of which the same may be simply connected with the chain 58.

The connecting member 74 is provided with an integrally formed collar or flange 80 at one end and a detachable collar or flange 81 at its other end, preventing disengagement thereof from the slot 78, the collar 81 being threaded to a stem 82 extending from the socketed member so as to provide for interchangeable use of various connecting members as suggested above, and is prevented from turning movement thereon by a removable pin 83. The collar 81 may be provided with a turn button or hand wheel enlargement 84 at one end to facilitate rotation of the socketed member.

Adjustment of the carriages 57 to the requirements of tubes of various diameters is provided for by supporting the track beams 54 on vertically adjustable members comprising cross bars 85 secured between vertically movable members 86 guided in their vertical travel by bolts 87 at the ends of cross heads 88 slidable in vertical parallel slots 89 formed in the standards. The travel of these members 86 is impelled by a threaded connection of the members 86 with rods 90. These rods 90 are arranged in opposing pairs and are conveniently driven by hand wheel shafts 91 journaled in the standards, and having mitre gear connection 92 with said rods; the shafts 91 having the usual hand-wheels 94 on their projecting ends. The rods 90 are supported in sockets 93 of the journal supports for the hand wheel shafts.

In connection with this mechanism there is provided in the present machine, mechanism automatically operable to stop the braiding unit upon the completion of a determined length of braiding on the mandrel. This mechanism comprises a rod 95 extending longitudinally of the take off structure, which is supported for limited longitudinal movement in brackets 96 secured to one of the two rods 51.

A collar 97 is mounted on the rod 95 for adjustment therealong and is adapted to be held in adjusted position by set screw 97a. The collar has thereon a lug 98 extending across the path of one arm of a two arm lever 99 pivoted to the carriage 75 by means of a pin 100, the lower arm 101 of the lever being yieldingly connected to a lug 102 on carriage 75 by a helical spring 103, the tension of which may be adjusted by bolt 104 threaded to the lug and forming the connection between the same and the spring.

Rod 95 has fixed thereon spaced collars 105 between which prongs 106 of the forked

arm 107 ride above and below the rod. This arm is secured to the upper end of a vertical shaft 108 which is journaled to one of the standards 50, and has a bell crank 108a at its lower end. One arm of this bell crank is connected to the supporting structure by spring 110 whereby the arm 107 is maintained normally in its position transversely of the track. Its other arm is connected through link 112, bell crank 113, link 114 in train with crank arm 111 secured to the end of shaft 35 and since the arm 34 is also secured to this shaft rocking thereof through the connection here described will release rod 32.

When the desired length of braid has been produced on the moving mandrel B, the lever 99, moving with the mandrel, will strike against stop lug 98 of collar 97 and shift the latter, and consequently rod 95, the distance necessary to release rod 32, and thus stop the machine by shifting the belt from drive pulley 28 onto the idler pulley 29, irrespective of any control by the braiding mechanism.

The foregoing description is thought to fully set forth the present improvements in construction and operation as specifically applied to the known type of braiding mechanism indicated; it being readily understood from such description that the invention relates to the novel take-off mechanism characterized essentially by the means provided for automatically stopping the braiding mechanism by action of the moving mandrel, upon completion of a determined length of tubing braided thereon; as clearly defined in the claims.

What I claim is:

1. In a machine for the manufacture of braided tubing comprising braiding mechanism and a mandrel movable along a course past the braiding mechanism and upon which the tubing is braided, take off mechanism for receiving and supporting the mandrel as it passes from the braiding mechanism; and means operable through movement of the mandrel for automatically stopping the braiding mechanism when a determined length of tubing has been braided.

2. In a machine for the manufacture of braided tubing comprising braiding mechanism and a mandrel passing along a course past the braiding mechanism and upon which the tubing is braided, take off mechanism affording a support along which the mandrel moves after being braided upon; means movable with the mandrel along said support and means adjustable along the course, said means cooperating to stop the braiding mechanism when a determined length of tubing has been fabricated thereon.

3. In a machine for the manufacture of braided tubing comprising braiding mechanism and a mandrel passing along a course past the braiding mechanism and upon which the tubing is braided, take off mechanism

comprising a support, a carriage movable along the support and attachable to the mandrel, a rod extending the length of the support and mounted thereon for movement lengthwise thereof, a member adjustable along the rod and means on the carriage adapted to cooperate therewith to shift said rod and means connected with the rod and operable by the shifting thereof for stopping the operation of the braiding mechanism.

4. In a machine for the manufacture of braided tubing comprising braiding mechanism and a mandrel movable past the braiding mechanism and upon which the tubing is braided, take off mechanism to receive said mandrel as it passes from the braiding mechanism, a carriage movable along the take off mechanism and attachable to the mandrel, a rod movable longitudinally of the take off mechanism in parallelism with the movements of the carriage, a member adjustably fixed on the rod, a member on the carriage adapted to contact therewith for shifting the rod, one of said members being yieldably mounted, and mechanism operable by the shifting of the rod for stopping the braiding mechanism.

5. In combination with a braiding unit and a mandrel passing therethrough, take off mechanism positioned to receive said mandrel as it passes from the braiding unit, said mechanism including a flexible endless belt of rigid link members; arranged along a course, means for attaching the mandrel to said belt and means for moving said belt along said course.

6. In combination with a braiding unit and a mandrel adapted to pass therethrough; take off mechanism including a track, carriages movable therealong and adapted to receive the braided mandrel from the braiding unit, an endless belt attached to the carriages and movable along the track, and means for attaching the mandrel to the belt.

7. In combination with a braiding unit and a mandrel adapted to pass therethrough; take off mechanism including a track, carriages movable therealong and adapted to receive the braided mandrel from the braiding unit, an endless belt of rigid links attached to the carriages and movable along the track, and means for attaching the mandrel to the belt.

8. In a braiding machine including braiding mechanism, a mandrel and take off mechanism positioned to receive the mandrel from the braiding mechanism; said take off mechanism including a vertically adjustable track, a flexible belt of non-elastic links, and carriages attached to the belt and movable on the track, a cut out for stopping the operation of the braiding mechanism, means adapted to be fixed in adjusted positions along the track inoperably connected with the cut out, and a member movable with the mandrel

adapted to operate said cut out through said means and incident to said movement.

9. A machine for the manufacture of braided tubing, a braiding unit, a mandrel movable along a course thereby, and take off mechanism for receiving the mandrel as it passes from the braiding unit; said take off mechanism including tracks positioned to receive the mandrel as it passes from the braiding unit, a carriage on the tracks, and vertically adjustable means on the carriage for attaching the mandrel thereto.

10. In combination with a braiding unit and a mandrel movable along a course therethrough; take off mechanism providing a support for the mandrel, said support being vertically adjustable in the take off mechanism radially of the position of the mandrel thereon adapting the take off support to the manufacture of tubing of various diameter.

11. In combination with a braiding unit and a mandrel movable along a course through the unit; take off mechanism including a vertically adjustable track, a carriage movable therealong, a member vertically adjustable on said carriage and attachable to said mandrel and means for moving said carriage along said track.

In testimony whereof I affix my signature.
